BINDING DEVICE

Charles E. Emmer, Chicago, Ill., assignor to
Cercia, Inc., Chicago, Ill., a corporation of
Illinois

Application October 16, 1935, Serial No. 45,175

6 Claims. (Cl. 129—1)

This invention relates to improvements in binding devices.

One object of the invention is to provide a binding device for perforated loose leaves, pamphlets or the like which is formed preferably of sheet material, such as metal, and comprises arcuate binding arms which inter-engage at the free ends by telescopic action to provide rings enabling the bound sheets to be turned freely to open or closed position.

Another object of the invention is to provide a binding device formed of a single sheet of material having arms the margins or marginal portions of which are folded over one face of the arms to provide a double thickness of material which not only stiffens the arms but provides means for effecting a relatively smooth interlocking engagement between the ends of the arms after the sheets have been assembled on the binding device.

Other objects relate to various features of construction and arrangement of parts which will be apparent from a consideration of the following specification and accompanying drawing, where-25 in certain embodiments of the invention are shown for the purpose of illustration. In the drawing:

Figure 1 is a broken perspective view of a binding device shown in closed or binding position, sheets and covers being indicated by dash lines.

Figure 2 is a broken perspective view of the device in open position.

Figure 3 are broken enlarged detail views in perspective of the mutually telescopic ends of the binding arms.

Figure 4 is a development of the binder, some of the arms being shown partially formed.

Figure 5 is a broken perspective view of a modified form of binding device.

Figure 6 is a sectional view taken on line 6—6 of Figure 5.

Figure 7 is a broken perspective view of a further modification of the invention.

Figure 8 is a broken perspective view of another modification.

In Figures 1 to 4 of the drawing, 10 indicates a central strip having integral laterally extending arms which preferably are stamped from a single sheet of metal. Arms 11 extend from one edge of the strip and arms 12 from the opposite edge as illustrated in Figure 2. Between adjacent arms of one group such as arms 11, tabs 13 are provided.

The arms of both groups have the free ends

reduced in width to form tongues or projections 11a, 12a which preferably are rounded at the extremities. The longitudinal margins of the arms 11 and 12 constitute flanges 11b and 12b respectively, which are adapted to be folded over a face of the respective arms to stiffen the same, to provide smooth edges and to provide recesses adjacent the bases of the tongues for receiving the tongues of the opposite arms. The flanges 11b, 12b are spaced slightly from the faces of 10 the outer or free ends of the arms but may be pressed into close contact with said arms at the opposite ends if desired. The spacing of the flanges from the arms as mentioned provides recesses for receiving the tongues or projections 15 of the opposite arms.

Figure 4 illustrates certain of the flanges 11b, 12b folded over one face of the respective arms. It will be noted in Figure 4 that flanges 11b are folded over the lower faces of arms 11 and that 20 flanges 12b are folded over the upper face of arms 12. When the flanges of the arms have been folded as above mentioned the arms 11 and 12 are given the arcuate form shown in Figure 2 which is less than a semi-circle. The strip 10 25 is folded along its longitudinal center, indicated by line 10a in Figure 4, and the tabs 13 are folded over the opposite edge of the strip to retain the strip firmly in folded position. The binder is then in the form illustrated in Figure 2 and is 30 ready for receiving the sheets to be bound.

The sheets 14 indicated by dash lines in Figure 1, are perforated at 15 to receive the arms 11 and 12 and may be placed on the arms with the strip 10 disposed midway between the covers 16, 35 17 or, if preferred, with the strip 10 disposed adjacent the back cover. The open ends of the arms then are pressed together, the tongues 11a entering the recesses 12c formed between the folded over flanges 12b and the adjacent faces 40 of the arms, and the tongues 12a entering the corresponding recesses 11c.

Due to the stiffening effect produced by folding over the flanges 11a and 12a and the double thickness of the strip 10, thin metal may be employed which results in a relatively smooth joint at the connected ends of the arms. The thickness of the metal is considerably exaggerated in the drawing as will be appreciated. The relative dimensions of the projections or tongues 11a, 50 12a and the recesses 11c, 12c may be such as to provide a tight frictional fit to retain the arms in closed position during use.

To further restrain withdrawal of the tongues 11a and 12a from the respective recesses of the 55

opposite arms, the tongues may, if desired, be provided with outwardly pressed portions 18 which during the closing operation snap past or into engagement with cooperating portions 19 of the opposite arms.

Due to the mutual telescopic arrangement wherein the tongues 11a and 12a of the arms enter recesses 12c, 11c respectively, the closing of all the arms can be effected expeditiously by 10 suitable mechanism (not shown) since each tongue 11a constitutes a guide for directing its mating tongue 12a into the recess 11c and each arm 12a constitutes a guide for directing the corresponding end 11a into the recess 12c. To effect this result the curvature of the ends 11a, 12a is such that as the arms are pressed toward closed position the paired tongues 11a, 12a will move into contact and serve to guide each other into the respective recesses.

20 The modification of the invention shown in Figures 5 and 6 corresponds to the form shown in Figures 1 to 4 inclusive, except that the back strip 20 of Figures 5 and 6 extends inwardly of the binder instead of outwardly. The change is 25 effected by folding the back strip 20 along its center line in a direction opposite the direction of fold of strip 10.

20 Tabs 21, corresponding to tabs 13, are also provided for securing the edges of the strip 20 against separating movement. The remaining portions of the device of Figures 5 and 6 are similar in all respects to the form first described and are given similar identifying reference characters. In both described forms of the invention, 35 the back strips 10 and 20 may be disposed within the bound edges of the sheets either centrally thereof or between the back cover and the last bound sheet. If desired, however, the strips may be disposed outwardly of the bound sheets.

40 In Figure 7 the strip 22 is not folded along its center line, as in the above modifications, but is flat or slightly curved in cross section, as illustrated. Tabs 23, integral with the strip and disposed between adjacent arms 11 and 12 are folded 45 over the inner face of the strip to stiffen it and provide smooth edges therefor. The strip 22 will be disposed along the bound edges of the sheets, and provides a backing upon which indicia such as the title, volume, number, or like matter can be attached.

45 In this form of the invention half the perforated sheets may be placed on one group of arms, and the remaining sheets on the other group of arms prior to pressing the arms to closed position or all the sheets to be bound and the covers, if any, may be placed on one arm if desired, unless the number of sheets is too great, and the arms thereafter moved to closed position and the sheets distributed upon both arms. Since the 50 construction of the arms of the binder shown in Figure 7 is the same as the arms of Figures 1 to 4, similar reference characters are employed to designate corresponding parts, and it is believed no additional description of the same is 55 required.

55 In Figure 8 the arms 24 and 25 are arcuate but due to the relative size and shape of the back strip 26 the binding is not circular in cross section. The arms 24 and 25, while preferably integral with the back strip as in the previously 60 described forms of the invention, have their margins 24a, 25a respectively folded over the inner face of the arms in both instances. The arms 24 are provided with tongues 24b extending 65 arcuately from the outer face thereof while arms

25 have tongues 25b formed as extensions of the flanges 25a. The tongue 25b of each arm 25 is thus formed of two parts.

One advantage of this arrangement is that by 5 folding the flanges of both arms over the inner faces of the respective arms 24, 25, no seams or spaces are formed on the exposed or outer surfaces of the arms.

After the perforated sheets to be bound are inserted on the arms, the latter are pressed into 10 mutual telescopic relation wherein tongues 24b enter recesses 25c and tongues 25b enter recesses 24c. The relative dimensions of the cooperating 15 arms and recesses can be such as to provide a friction fit which retains the arms in engagement or the arms may, if desired, be provided with portions 27, 28, the former of which snaps past the latter when the arms are pressed to closed position to restrain separation of the inter-engaged 20 ends to provide a permanent binding.

While I have shown and described certain embodiments of my improvements for the purpose of 25 illustration, I do not wish to be restricted specifically thereto except as so limited by the appended claims.

I claim:

1. A binder comprising a strip and oppositely directed arcuate arms extending therefrom arranged in cooperating pairs adapted to be pressed into ring form, said arms being of sheet material 30 and provided with projections on the free ends of certain of said arms and recesses in the mating arms each for telescopically receiving said projection of the other arm of the pair for connecting said ends together.

2. A binder comprising a strip and two groups of integral oppositely directed arcuate arms, the arms of one group having marginal portions folded over one face of the arms to provide recesses adjacent the free ends of the arms, the arms of the opposite group having free ends arranged to pass into said recesses to provide closed binding rings, and means for retaining 40 said rings in closed position.

3. A binding device comprising a strip provided with two groups of oppositely directed arcuate arms adapted to be pressed into ring form, each of said arms being paired with an arm of the other group and provided with longitudinal recesses adjacent the free ends thereof, said arms each having a free end arranged to pass into the recess of the other arm of the pair to provide 50 mutually telescopic connections for the arms when pressed into ring form.

4. A binding device comprising a strip provided with oppositely directed arcuate arms adapted to be pressed into ring form, said arms having projections at the free ends thereof and recesses at the rear of said projections, said arms being arranged in pairs whereby when each pair is 60 pressed into ring form the projection of each arm is disposed within the recess of its mate to provide mutual telescopic connections for the arms.

5. A binding device comprising a strip provided with a plurality of arcuate arms extending from the longitudinal edges of the strip and arranged in pairs adapted to be pressed into ring form, and means for connecting the free ends of each pair of said arms comprising projections and projection-receiving recesses adjacent each of said 70 free ends, the recess of one arm of each pair being aligned with one face of the projection of said arm, the recess of the other arm of each pair being aligned with the opposite face of the projection of said arm, the arrangement being such 75

that as said arms are pressed to ring form the projection of each arm serves as a guide to direct its mate into the cooperating receiving recess.

6. A binding device comprising a strip having integral arcuate arms arranged in pairs extending from opposite edges thereof, and adapted to be pressed into ring form, said arms having longitudinal marginal portions folded over a face

thereof to provide tongue receiving recesses adjacent the free ends of the arms, and a tongue projecting beyond the forward end of each recess and arranged to enter the recess of an opposite arm when said pairs of arms are pressed into ring form to connect the free ends of each pair of arms.

CHARLES E. EMMER.
